United States Patent Office.

THOMAS R. BEARSE, OF TAUNTON, MASSACHUSETTS, ASSIGNOR
TO TAUNTON TACK COMPANY, OF SAME PLACE.

Design No. 3,613, dated August 17, 1869.

DESIGN FOR A NAIL OR TACK.

The Schedule referred to in these Letters Patent and making part of the same.

To all persons to whom these presents may come:

Be it known that I, THOMAS R. BEARSE, of Taunton, of the county of Bristol, of the State of Massachusetts, have invented or produced a new ornamental Design for a Nail or Tack; and do hereby declare the same to be fully described in the following specification, and represented in the accompanying drawings, of which—

Figure 1 is a perspective view of a tack as made with the crossed bars or cross in relief on its head;

Figure 2 is a side elevation; and

Figure 3, a top view of such tack.

In carrying out the design, I form the tack or nail with a cross in relief on the upper flat surface of its

head, the arms of the cross being of equal or about equal lengths, and each having the form, in transverse section, of the segment of a circle, or a close approximation thereto.

In the drawings—

a denotes the shank, and *b*, the head of the tack, they being of the usual form.

C is the cross, formed in relief on such head.

I claim the above-described design or configuration of a nail or tack.

THOS. R. BEARSE.
